Inventor:

UNITED STATES PATENT OFFICE.

JOHN H. FENTON, OF CHICAGO, ILLINOIS.

ROLLER-SKATE.

SPECIFICATION forming part of Letters Patent No. 331,291, dated December 1, 1885.

Application filed October 28, 1884. Serial No. 146,654. (No model.)

To all whom it may concern:

Be it known that I, JOHN H. FENTON, residing at Chicago, in the county of Cook and State of Illinois, and a citizen of the United States, have invented a new and useful Improvement in Roller-Skates, of which the following is a full description, reference being had to the accompanying drawings, in which—

Figure 1 is a view showing one wheel in elevation and the other in section, with the frame partly in section; Fig. 2, a side elevation of one of the wheels; Fig. 3, an end elevation of one of the thimbles with the engaging points extended; Fig. 4, a longitudinal section of one of the thimbles with the engaging points turned down; Fig. 5, a side elevation of the wheel with the end of the hub slotted; Figs. 6 and 7, details of a thimble for the form of wheel shown in Fig. 5; Figs. 8 and 9, a side elevation and cross-section of the skate-frame with the ends of the bearing portion slotted to receive thimbles of the form shown in Figs. 6 and 7.

The present manner of mounting the wheels of roller-skates is objectionable, for the reason that the axle or spindle hole wears very rapidly in use, the result being that the wheel will wobble, thereby rendering the skate noisy and unsafe in use, and, as heretofore constructed, in order to overcome the wear it has been necessary to replace the wheels with new ones, which is somewhat expensive.

The object of this invention is to overcome this objection in roller-skates by enabling the wear to be readily taken up without supplying new wheels in full.

The object of my invention I accomplish in the manner hereinafter described and claimed.

In the drawings, A represents the wheels; B, the thimbles; C, the axle; D, the frame.

The wheels A may be made of wood or other suitable material, either in the form shown or other desired form, so as to have a hub or center, through which is the hole for the passage of the axle. Two thimbles, B, are used for a wheel, and are each in length not quite equal to one-half the length of the hub, so as to leave a small space between their inner ends when in place, which forms an oil-receptacle.

The thimbles may be made of brass or other suitable metal, cast or otherwise formed into shape to have an exterior corresponding in diameter, or nearly so, to the diameter of the hub-opening, so that the thimbles can be driven into such opening, and the outer end of each thimble, in the form of construction shown in Figs. 3 and 4, is provided with a flange, b, having projecting points b', which points can be turned down and forced into the wheel around the hub-opening as the thimble is driven to place, which points hold the thimble against rotation independent of the wheel. The interior diameter of the thimbles corresponds to the diameter of the axle, so that when the wheel is on the axle it will fit so as to revolve smoothly.

As shown in Figs. 6 and 7, the exterior end of each thimble is provided with a rib or lug, c, which enters a recess, a, formed in the end of the hub, and furnishes a means for locking the thimble to the wheel.

As shown, the exterior ends of the thimbles are protected against the wear of the axle-pin by a washer, d, interposed between it and the pin.

The frame D is of the usual construction, having a bearing portion in which the axle C runs, and this bearing portion is protected against wear by thimbles corresponding to those shown in Figs. 6 and 7, the ends of the bearing portion of the frame having recesses e to receive the ribs or flanges c. The thimbles are placed in the hubs by driving or forcing them therein, and when in place are locked to the hub either by the points b' or the ribs or lugs c, and the thimbles for the bearing portion of the frame are inserted in place and held by the locking lugs and notches.

In use, when the thimbles become worn on their interior so as to allow play of the wheel on the axle, the difficulty can be remedied by slipping the wheel from the axle, inserting new thimbles with the interior diameter unworn, and replacing the wheels, and for this purpose the thimbles can be made up and supplied to parties using the skates, thus enabling them to do their own repairing, and the same operation can be performed for the frame-bearing portions.

- The skates now in use, as the opening in the hub becomes worn, can be made perfect again by simply inserting the thimbles, and when the thimbles are in position the space or opening between their interior ends furnishes a receptacle for oil or other lubricant, by which the parts can be kept properly oiled or lubricated for a considerable length of time, and this space between the ends of the thimbles also forms a receptacle for the cutting or wearing of the parts, and thereby prevents such cutting and wearing from increasing the wear in use by remaining between the axle and the bearing.
- As shown in Figs. 6 and 7, the exterior flange of the ends of the thimble is omitted; but such flange could be formed on the ends or projections extending down therefrom, and this flange forms a stop for limiting the distance that the thimble enters the hub-opening, and at the same time furnishes a smooth side bearing for the wheel, and the flange is prevented from being worn by interposing washers *d* between it and the holding-pin.
- The carriage or frame *D* being made of metal, necessitates the forming of the recesses *e* and making the thimbles with lugs *c*.

Thimbles of the construction shown and described, when made of sufficient size, can also be used with other forms of wheels than those designed for roller-skates with great benefit and advantage, as by their use the wheels, when they become loose on the axle from wear, can be tightened by simply withdrawing the old thimbles and replacing them with new.

35

What I claim as new, and desire to secure by Letters Patent, is—

1. The cylindrical thimbles *B*, provided at their outer ends with interlocking points or lugs to enter recesses in the outer faces of the wheels around the hub-opening, substantially as described.
2. The thimble *B*, provided at its outer end with a laterally-projecting flange, *b*, provided with inwardly-extending points *b'*, to enter the face of a wheel around the hub opening, substantially as described.

JOHN H. FENTON.
